UNITED STATES PATENT OFFICE.

PETER DOUROS, OF ST. LOUIS, MISSOURI.

SHOE-SHINING APPARATUS.

1,371,875.

Specification of Letters Patent. Patented Mar. 15, 1921.

Application filed April 14, 1919. Serial No. 289,893.

To all whom it may concern:

Be it known that I, PETER DOUROS, a citizen of Greece, residing at St. Louis and State of Missouri, have invented new and 5 useful Improvements in Shoe-Shining Apparatus, of which the following is a specification.

This invention relates to improvements in devices for shining shoes and the principal object of the invention is to provide 10 power driven means for actuating a number of instruments for polishing and drying the shoes.

Another object of the invention is to provide 15 means for coupling and uncoupling a flexible shaft, which drives the implements to and from the power shaft so that the implements can remain stationary when not in use.

20 Still another object of the invention is to provide means for quickly and easily removing one implement and replacing it by another so that the different implements may be used on the flexible shaft.

25 The invention also consists in certain other features of construction and in the combination and arrangement of the several parts, to be hereinafter fully described, 30 illustrated in the accompanying drawings and specifically pointed out in the appended 35 claims.

In describing my invention in detail, reference will be had to the accompanying drawings wherein like characters denote like 35 or corresponding parts throughout the several views, and in which:—

Figure 1 is an elevation partly in section showing one way of carrying out my invention;

40 Fig. 2 is a view taken at right angles to Fig. 1 with parts in section;

Fig. 3 is a sectional view of the drying implement;

Fig. 4 is a view of one of the brushes.

45 In these views 1 indicates a frame which is adapted to be secured to any desired support and said frame consists of a base 2 and the arms 3. The arms at their upper ends form journals for the power shaft 4 which 50 is driven by a motor 5 or any other suitable source of power. The base 2 is provided with a slot 6 and a housing 7 is slidably supported on said base and is secured thereto by a screw 8 which engages said slot. 55 Within this housing is located a hollow

shaft 9 through which the power shaft 4 passes. The outer end of this hollow shaft is stepped as at 10 to provide one part of a coupling; the other part 11 of which is connected with the power shaft. The inner end of the hollow shaft is enlarged and this enlarged part 12 is provided with a spiral gear 13. The hollow shaft 9 is removably held in the housing by means of the screw-threaded plug 14 closing one end of said housing. The housing also supports a spiral gear member 15 which engages with the member 12 so that the rotary movement of the hollow shaft, when it is connected with the power shaft, will be communicated to said member 15. This member is connected with the flexible chain 16 inclosed by the tubular member 17, forming the well-known type of flexible shaft. The casing is provided with an extension sleeve 18 which 70 forms a bearing for the cylindrical part 19 of the member 15.

The tubular member 17 at its outer end, 75 carries a tubular part 20 and the chain has its outer end connected with a cylindrical part 21 which is stepped at its outer end to form one part of a clutch 22, this stepped part projecting from the end of the tubular part 20. Each of the implements carries a sleeve 23 which is rotatably secured thereto 80 and this sleeve is adapted to fit over the tubular part 20. The sleeve is provided with a notch 24 which is adapted to be engaged by a finger latch 25 located adjacent the end of the flexible shaft. By this means 85 the implement is detachably connected with the shaft. Each implement also has secured thereto a cylindrical member 25 which projects into the sleeve 23 and has its end stepped to form the other member 26 of the 90 clutch. In this way when the two parts of the clutch are placed in engagement and the sleeve connected with the end of the shaft, the rotation of the flexible chain will cause 95 the implement to be actuated.

100 It will, of course, be understood that any desired form of polishing implement may be used with my device. The implement shown attached to the device is a buffer, the core 27 of which is removably secured to the stem 105 28 of the cylindrical part 25 by the nut and washer 29.

Fig. 3 shows a drying implement which consists of a fan 30 attached to the stem 28' and a guard 31 surrounding the stem. 110

Fig. 4 shows a brush 32, of ordinary construction, secured to the stem 28.

It will thus be seen that an implement can be easily and quickly detached from the flexible shaft and another implement connected with said shaft so that the operator may use different implements in applying the polish to the shoes.

The means for moving the housing into operative and inoperative position, consists of a lever 33 pivoted to the base 2 and connected with the lower part of the housing by a link 34. Thus by operating said lever, the housing may be pushed over to throw the two parts 10 and 11 of the clutch into engagement to cause the flexible shaft to be rotated by the power shaft and when the operation of polishing the shoes is completed, the lever is moved in the opposite direction to release the clutch means.

In carrying out my invention in a shoe shining establishment, the power shaft 4 would extend along the row of chairs and a flexible shaft would be provided for each chair. A set of polishing implements would be provided for each chair. In this way the shoes of a customer can be quickly polished so that each operator can handle a greater number of customers than he could by the hand method.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A device of the class described comprising a drive shaft, a housing slidably mounted thereon, a hollow shaft carried by the housing and through which the drive shaft passes, clutch means on the drive shaft and hollow shaft, a driven shaft, gears for connecting the driven shaft with the hollow shaft, and means for moving the housing to throw the clutch means into and out of engagement. 40

2. A device of the class described comprising a supporting frame, a drive shaft journaled therein, a housing slidably mounted on the frame, means for moving the housing thereon, a hollow shaft carried by the housing and through which the power shaft passes, clutch means carried by the hollow and power shafts, a driven shaft carried by the housing, and gears connecting the driven shaft with the hollow shaft. 50

3. A device of the class described comprising a frame having a slot therein, a power shaft journaled in said frame, a housing through which the power shaft passes, mounted on the frame, fastening means connecting the housing to the frame and engaging the slot, a lever connected with the housing for moving the same, a hollow shaft carried by the housing and through which the power shaft passes, clutch means carried by the hollow shaft and power shaft, a flexible shaft carried by the housing, and gears connecting the flexible shaft with the hollow shaft. 60

In testimony whereof I affix my signature.

PETER DOUROS.
